UNITED STATES PATENT OFFICE.

EMIL J. BERGER, OF PHILADELPHIA, PENNSYLVANIA, ASSIGNOR TO DEXDALE HOSIERY MILLS, OF LANSDALE, PENNSYLVANIA, A CORPORATION OF PENNSYLVANIA.

DESIGN FOR HOSIERY.

Application filed March 5, 1929. Serial No. 30,303. Term of patent 14 years.

To all whom it may concern:

Be it known that I, EMIL J. BERGER, a citizen of the United States, residing at Philadelphia, in the county of Philadelphia and State of Pennsylvania, have invented a new, original, and ornamental Design for Hosiery, of which the following is a specification, reference being had to the accompanying drawings, forming part thereof.

In the drawings:

Fig. I is a side elevation of a stocking showing my new design; and

Fig. II is a rear elevation of the heel and ankle portion of the stocking shown in Figure I.

I claim:

The ornamental design for hosiery, as shown.

EMIL J. BERGER.
